FIG 5.

FIG 6.

UNITED STATES PATENT OFFICE.

SARAH FLEWELLEN BRUNDIDGE, OF NEW YORK, N. Y.

SUPPORTING GIRDLE.

Application filed June 25, 1925. Serial No. 39,552.

This invention relates to a supporting girdle, and particularly to a construction adapted to support the excess flesh adjacent the diaphragm of a person wearing a low bust corset, or as a garment independent of such a corset.

Under ordinary conditions in the use of such a low front corset by women the excess flesh and fat intermediate the chest and the abdomen is pressed upward when the wearer is in bending or sitting position, causing discomfort and an unsightly appearance. The enlarged diaphragm is often caused by the wearing of corsets too low at the bust but this type of corset is frequently much more comfortable in use than the high front type and I have provided a girdle adapted to be worn partially beneath the front of a low bust corset and supplementing the same to provide a support for the flesh above the corset to hold in and flatten protruding fat or flesh in the region of the stomach and diaphragm, thus providing comfort and a proper support without affecting the waist line of the garment.

Such a construction is particularly desirable for use by stout persons as it avoids the necessity of wearing a high bust corset while providing the support necessary at the proper point and permitting the use of the more comfortable low bust type, especially by women engaged in housework or other occupations which require frequent change of position.

The invention has for an object to provide a girdle comprising a substantially ovate pad having securing bands extending downward in opposite directions from the upper portion thereof and adapted to be secured about the waist of the wearer.

A further object of the invention is to provide a stayed pad having free elastic securing bands secured only at the upper portion thereof and extending downward in opposite directions so as to apply an elastic pressure to the upper portion of the pad which projects above the corset used in connection therewith.

Another object of the invention is to provide a pad provided with vertical stays and supporting means, together with a spreading stay extending transversely of the upper portion of the pad and removably mounted in pockets at the opposite sides thereof.

Other and further objects and advantages

of the invention will be hereinafter set forth and the novel features thereof defined by the appended claims.

In the drawing:

Figure 1 is a front elevation of the invention applied to a corset;

Figure 2 is a rear elevation thereof;

Figure 3 is a detail front elevation of the girdle; and

Figure 4 is a similar rear view thereof.

Figure 5 is a perspective of another means for sustaining the girdle in position, and

Figure 6 is a rear elevation of the front of this form.

Like numerals designate corresponding parts throughout the several figures of the drawing.

The pad may be formed of any desired material, preferably of a fabric, and comprises a substantially ovate body 10 as shown, 75 provided with a series of parallel, vertically disposed stays 11 secured in pockets thereon. Extending longitudinally of the pad a strap 12 is provided and secured intermediate of the stays 11 by eyelets 13 or similar fastening devices so as to resist any stretching or distortion of the pad and maintain the same in proper shape.

For the purpose of securing the pad upon the wearer elastic bands 14 are provided and secured to the pad at its apex or upper portion, as indicated at 15, these bands being otherwise free from the pad and extending downward in opposite directions so as to pass about the waist line of the wearer to the back of the corset. To prevent displacement of the elastic bands relative to the upper edge of the girdle they are connected by an elastic band 19.

The free ends of the elastic bands are 95 provided with straps 16 which may be crossed at the back and brought forward and secured together by tying or otherwise at the front of the garment. These bands apply a yielding tension to support the 100 weight of the flesh bearing against the upper portion of the pad so that the same may be comfortably worn and not pressed unduly against the wearer when in sitting or bending position.

In order to hold this upper portion of the pad in proper extended position and prevent wrinkling thereof it has been found desirable to provide a spread stay 17 removably mounted at its opposite ends in 110

pockets 18 secured to the opposite sides of the upper portion of the pad.

In the application of the invention the lower portion of the girdle is inserted with 5 in the bust portion of the corset as shown in Figure 1, with the elastic band connecting the supporting straps substantially at the upper edge thereof. This provides a stayed support extending upward at the 10 front of the corset and yieldingly held in contact with the diaphragm or fleshy portion of the wearer intermediate the waist and chest. The girdle is secured by simply passing the elastic bands to the back there- 15 of and bringing forward the tapes for connection together. The girdle thus holds the excess flesh in position so that the bust of the wearer is not pushed upward when in bending or sitting position as the edge of 20 the girdle within the corset slips downward permitting a relative movement of these parts so that the girdle may assume its original position when the person is in stand- 25 ing position.

It has been found particularly desirable to avoid the use of bands or girdles extending about the waist line of the wearer as they are uncomfortable and do not provide support at the desired portion but rather 30 force upward the flesh at all sides of the bust, tending to draw in the waistline at the back. By contrast, the present invention provides for depressing, and, therefore, sup- 35 pressing the flesh at the central area of the bust.

The invention provides a simple form of girdle adapted for application to corsets already in use without attachment thereto, and may be also used independently of such 40 corsets for effecting a similar support of the excess flesh of the wearer.

The girdle is adapted to be applied as an independent garment from the corset and is so shown in Figures 5 and 6 wherein the 45 pad 20 forming the front of the garment is provided with stays 21, a cross strap 22 and a brace 23 all substantially similar to those before described. At each side of this pad 20 rearward extensions 24 are provided and 50 connected at the back by a suitable lacing 25, thus forming a supporting band about the waist or body of the wearer. In this modified form of the invention, the elastic bands 26 are attached at 27 to the pad as 55 before described and carry at their free ends

the securing tapes 28 which may be crossed at the back and brought again to the front and there tied or otherwise secured. The elastic bands 26 are free beyond their attached portion at 27 and are retained by 60 loops 29. The pad is also provided at the lower portion of the front with suitable garment supporters as shown at 30 and similar supporters 31 are also dependent from the rearward extensions from the pad. 65 These provide a complete and independent garment by which the advantages of the girdle in supporting the surplus flesh may be secured without cooperation with a corset. The attachment of the garment supporters 70 provides for free movement at the hips and limbs, while holding the hosiery and also securing the advantages of the supporting girdle.

The specific details of construction have 75 been herein shown and described but the invention is not confined thereto as changes and alterations may be made therein without departing from the spirit thereof as defined by the following claims.

Having thus described my invention, what I claim as new and desire to secure by Letters Patent of the United States is:—

1. A girdle comprising a pad having a flexible apex at its central portion and attaching bands secured only at said apex with free ends extending downwardly in opposite directions therefrom in constantly diverging lines to stress said apex downward and inward.

2. A girdle comprising a pad having a flexible apex at its central portion and attaching bands secured only at said apex with free ends extending downwardly in opposite directions therefrom in constantly diverging lines to stress said apex downward and inward, and an elastic connection extending between the free portions of said bands below said apex.

3. A girdle comprising a stayed pad having an upstanding apex and free elastic securing bands secured only at the apex of the pad and extending downwardly and rearwardly from said apex, an elastic band connecting the free portions of the securing bands, and a non-elastic strap extending transversely of the pad stays and secured intermediate thereof.

In testimony whereof I affix my signature.

SARAH FLEWELLEN BRUNDIDGE.
